UNITED STATES PATENT OFFICE

126,873

DESIGN FOR A MOUTHPIECE FOR A SPEAKING TUBE OF A PHONOGRAPH

William J. O'Neil, Atlantic Beach, and Leland Stanford Briggs, New York, N. Y., assignors to Dictaphone Corporation, New York, N. Y., a corporation of New York

Application November 26, 1940, Serial No. 96,827

Term of patent 14 years

To all whom it may concern:

Be it known that we, William J. O'Neil and Leland Stanford Briggs, both citizens of the United States and residents, respectively, of Atlantic Beach, in the county of Nassau and State of New York, and of New York, in the county of New York and State of New York, have invented a new, original, and ornamental Design for a Mouthpiece for a Speaking Tube of a Phonograph, of which the following is the specification, reference being had to the accompanying drawing, forming part thereof.

The figure shown in the drawing is a perspective view of a mouthpiece for a speaking tube of a phonograph, showing our new design.

The reverse side of this mouthpiece is a substantial duplicate of that shown in the drawing.

We claim:

The ornamental design for a mouthpiece for a speaking tube of a phonograph, substantially as shown and described.

WILLIAM J. O'NEIL,
LELAND STANFORD BRIGGS.
